WINDOW BRACKET

Bernard E. Mendelsohn, Waban, Mass., assignor to
Harvey Window Incorporated, Dorchester, Mass.
Filed Feb. 25, 1963, Ser. No. 260,741
10 Claims. (Cl. 189—76)

This invention relates to storm windows and more particularly comprises a new and improved storm window sash. This application is a continuation in part of my copending application Serial No. 84,416 dated January 23, 1961, now Patent No. 3,080,622, patented March 12, 1963.

In my earlier application supra, I disclose a multi-sash tilt-type storm window employing special brackets at the four corners of each sash. The brackets disclosed in that application form housings for latches which not only serve to support the window sashes in the window frame but in addition control the position of extendable flanges carried by the sashes that cooperate with the frame to effect a better weather seal.

The improved brackets disclosed in the earlier application comprise the first embodiment of this invention and provide a self-locking type of action which causes the parts of the brackets to engage firmly the side members of the sashes so that they do not in any way twist or tilt with respect to the top and bottom members of the sashes. Moreover, the brackets reduce the amount of staking required to form a permanent connection between the brackets and the side members of the sashes.

In another embodiment of this invention the physical characteristics of the brackets in the earlier application are utilized in both the horizontal top and bottom members of the sash as well as in the side members. Thus, a very firm fit is provided between the brackets and all of the sash frame parts. While in the window which employs the first embodiment of the present invention, an extendable flange forms part of each sash side, the window utilizing the second embodiment does not include the extendable flange and thus the configuration of the sash side members is appreciably different from that of the first embodiment.

My invention will be better understood and appreciated from the following detailed description of two embodiments thereof, selected for purposes of illustration and shown in the accompanying drawing, in which:

FIG. 1 is a fragmentary front elevation view of a sash constructed in accordance with my invention;

FIG. 2 is an enlarged fragmentary perspective view, partly in section, showing a portion of the sash of FIG. 1;

FIG. 3 is a cross-sectional view taken along the corresponding section line in FIG. 2;

FIG. 4 is a plan view of the bracket employed in the embodiment of FIG. 1;

FIG. 5 is a fragmentary side view of another embodiment of the sash constructed in accordance with this invention;

FIGS. 6, 7 and 8 are cross-sectional views taken along the corresponding section lines in FIG. 5;

FIG. 9 is a perspective view of the lower corner bracket employed in the sash of FIG. 5; and

FIG. 10 is a perspective view of an upper corner bracket employed in the sash of FIG. 5.

The embodiment of the storm sash shown in FIGS. 1-4 includes in its general organization a sash frame 10

2

having a side member 12, a top member 14, a bottom member 16 and glass 18. It will be appreciated that a second side member identical to the side member 12 shown in FIG. 1 extends parallel to the side member 12 on the other side of the sash.

The side member 12 is generally H-shaped in cross section as shown in FIG. 3 and includes generally parallel sides 20 and 22 interconnected by a web or cross member 24. The H-shaped cross-sectional configuration defines a pair of channels 26 and 28 disposed back to back and open in opposite directions. The channels are generally vertically oriented and extend from the top member 14 to the bottom member 16. A secondary channel 30 is formed within the general confines of the channel 28 and is defined by sides 32 and 34 and panel 36. The secondary channel 30 extends throughout the full length of the side member 12 and contains a length of weather stripping as suggested at 38. The weather stripping 38 is so positioned that it bears against the supporting or bearing surface of the storm window frame (not shown) when the sash is mounted in the frame.

The top member 14 and the bottom member 16 join the top and bottom of the side member 12 at mitered corners 40 and 42 shown in FIG. 1. The top member 14 and the bottom member 16 each include a channel identified at 44 and 46, respectively, that form continuations of the channel 28 of the side member 12 when the three parts are assembled together. The channels 44 and 46 open inwardly of the sash 10, that is, face the inside of the dwelling upon which the storm window is mounted.

Corner brackets 48 and 50 are employed to join the top member 14 with the side member 12 and the bottom member 16 with the side member 12, respectively. Corner bracket 50 is shown in cross section in FIGS. 2 and 3 and in plan view in FIG. 4. The bracket includes a horizontal arm 52 disposed in the channel 46 of the bottom member 16 and a vertical arm 54 disposed in the channel 28 of the side member 12. The horizontal arm 52 is composed of a face plate 56 and a pair of horizontally disposed and spaced apart flanges 58 and 60 which bear against the sides of the channel 46 in the bottom member 16. The face plate 56, the flanges 58 and 60, and the base of the channel 46 cooperate to define an enclosed track within which is mounted a latch 62 described in detail below.

The vertical arm 54 of the bracket 50 includes a face plate 64 which bears against the inner surface of the side 22 of side member 12 and a flange 66 disposed against the base of the channel 28 as defined by web 24. It will be noted particularly in FIG. 3 that the flange 66 and the plate 64 fit snugly within the channel 28. It will also be noted that a lip 68 is formed as an integral part of the side 22 of side member 12 and is provided with an undercut inner surface 70 which engages a mating beveled surface 72 formed on the end of the face plate 64 of the vertical arm 54. The undercut surface 70 of the lip 68 cooperates with the general character of the fit of the vertical arm 54 in the channel 28 to hold the vertical arm firmly in place. It also provides specific resistance against displacement of the vertical arm 64 in the channel 28 when the vertical arm is staked in place as suggested at 74.

The horizontal and vertical arms 52 and 54 of bracket 50 are approximately one inch in length and it is essential that in the relatively short distance provided a firm connection be made between the bracket arms and the bottom and side members of the sash. It is to be noted

that the corner bracket 48 which serves to interconnect the top member 14 and the side member 12 is virtually identical to the corner bracket 50 and specifically is provided with a tapered surface at the end of the face plate to form a beveled corner which cooperates with the undercut surface 70 provided on the lip 68 which extends the full length of the side member 12.

A retractable flange 80 is disposed within the channel 28 of the side member 12 and cooperates with a channel or track formed in the window frame (not shown) to enhance the weather tightness of the storm window. The retractable nature of the flange 80 permits the sash to be assembled readily as a tilt-type window within the frame, but yet provides the full protection of the track-type windows of the prior art. Because the flange 80 may be withdrawn wholly within the confines of the channel 28 in the side member 12, the sides may be tilted inwardly when the flange is so withdrawn to facilitate cleaning and removal, but when the sash is mounted in the frame and the flange extends into the track or channel of the frame, it forms a weather-tight seal along the sides of the sash.

The latch 62 slideable within the enclosed track defined by the horizontal arm 52 of bracket 50 and the base of channel 46 in the bottom member 16, includes an enlarged head 90 which rides along the side of the window frame in which the sash is mounted and may cooperate with stops formed inside of the frame to retain the sash in an open position. The latch carries an upwardly extending tongue 92 just rearwardly or inwardly of the head 90, that engages a slot 94 cut in the bottom of the panel 82 of the flange 80 to support the flange in the channel 28 of the side member 12. The tongue 92 has an enlarged base in the form of a shoulder 96 that serves to space the tongue 92 from the plate 66 of the vertical arm 54 of the bracket 50. Thus, as is shown in FIG. 2, the tongue 92 is spaced from the plate 66 a distance which is adequate to receive the tine 98 forming one side of the slot 94 in the flange 80. A similar arrangement is used to support the upper end of the flange 80.

The shoulder 96 serves as a guide or gage to facilitate the assembly of the sash frame. When the bottom member 16 is secured to the side member 12 by means of the bracket 50 and the latch 62 is disposed in the position shown in FIG. 2, the shoulder 96 spaces the tongue 92 from the inner surface of the plate 66 of the vertical arm of the bracket and the flange 80 may be slipped into the channel 28 formed in the side member. By running the flange 80 against the web 24 the tine 98 falls in place behind the tongue 92. Thus, what otherwise could be a problem in assembling the window is avoided. Similarly, when the top member 14 is connected to the side member 12 the tongue (not shown) on latch 102 will automatically align itself with the slot (not shown) at the top of the flange and slip into place.

In the embodiment of FIGS. 5-10 the sash 110 includes side member 112, top member 114, bottom member 116 and glass 118. A corner bracket 120 is employed to interconnect the side member 112 and the top member 114, and a second and different bracket 122 is employed to connect the side member 112 with the bottom member 116.

The side member 112 shown in FIG. 7 is an extrusion composed of generally parallel inner and outer sides 124 and 126. A generally L-shaped channel 128 is formed at the outer side of the member 112, which leaves a somewhat thickened outer section 130 in the side wall that is provided with a cavity 132 for supporting weather stripping 134. The L-shaped channel 128 is partially separated from an inwardly opened channel 136 by a pair of short ribs 138 and 140 facing one another on the inner faces of the sides 124 and 126. The ribs 138 and 140 define the inner extreme of the L-shaped cavity 128. An inclined wall 192 is provided at the outer extreme of the L-shaped channel and cooperates with the vertical arms of the brackets 120 and 122 in a manner described below.

The top member 114 shown in FIG. 8 is generally H-shaped in crosssection having inner and outer sides 142 and 144 connected by a web 146. The web 146 with the inner and outer sides define upwardly and downwardly open channels 148 and 150. The outer side 144 may carry a downwardly or upwardly extending flange 152 (a downwardly extending flange is shown) depending upon whether the sash is designed to be closed in a raised or lowered position within the frame of the window. The flange 152 shown is provided on the top member 114 of a sash which is closed in the lowered position and cooperates with a similar flange extending upwardly from the bottom member of a sash which is closed in a raised position within the frame to form a tongue and groove-like closure between them. It will be noted in FIG. 8 that the upper end of the inner side 142 of top member 114 is provided with a lip 154 which defines an undercut 156 substantially identical to the lip 68 in the side member 12 of the sash of the first embodiment.

The bottom member 116 shown in FIG. 6 is substantially identical to the bottom member 16 of the previously described embodiment. Thus, the bottom member 16 has an inwardly open channel 160 and an upwardly extending channel 162, and the channel 160 receives the horizontal arm of the corner bracket 122. In FIG. 6 the horizontal member is shown to include an upwardly extending flange 164 of the type which could cooperate with the flange 152 shown in FIG. 8 on the top member 114 when the two are disposed on separate sashes.

The bracket 122 shown in FIG. 8 has substantially all of the characteristics of the bracket 50 shown in the previous embodiment. Thus, the bracket includes a horizontal arm 166 which fits within the channel 160 of the bottom member 116. It will be noted in FIGS. 6 and 9 that the horizontal arm 166 has an inner face plate 168 and a pair of parallel horizontal flanges 170 and 172 which bear against the upper and lower sides of the channel 160 in the bottom member. In FIG. 6 it will be noted that a pair of ribs 174 are located at the mouth of the channel 160, and the ribs 174 cooperate with shoulders 176 provided in the flanges 170 and 172 of the horizontal arm 166 to retain the arm in the channel 160. The shoulders 176 are also provided with staking recesses 178 along each side of the horizontal arm, which receive the staking protrusions 178' or dimples formed in the ribs 174 at the mouth of the channel 160 of the lower member 116.

The horizontal arm 166 of the bracket 122 cooperates with the base of the channel 160 in the lower horizontal member 116 to define a sleeve for the latch 180. The latch 180 may be substantially identical to the latch 62 shown in the first embodiment but does not include the upwardly extending tongue 92, because the sash frame does not include an extendable flange of the type shown at 80 in the first embodiment. Accordingly, the latch 180 only serves to support the sash in the window frame (not shown) by means of its head 182 which extends out the end of the bracket horizontal arm 166.

The vertical arm 184 of the bracket 122 is substantially L-shaped in cross section just as the arm 54 of the bracket 50. In FIG. 7 the vertical arm 184 is shown to be identical in cross section to the L-shaped channel 128 formed in the side member 112. Thus, when the vertical arm 184 is inserted in the channel 128 the two together form a substantially solid cross section. It will be noted that the face plate 186 of the vertical arm 184, which is parallel to the face plate of the horizontal arm, lies flush against the inner surface of the side 124 of the side member 112 and the rib 188 of the vertical arm 184 bears against the sides of the ribs 138 and 140.

The outer edge of the face plate 186 of arm 184 is bevelled at 190 from the inner side thereof as shown in FIG. 7, and the bevel 190 cooperates with the similarly shaped inclined wall 192 defining the side of the L-shaped channel in the side member. The arm 184 and the side

member 112 are locked together by staking the side member at a few places as suggested at 194 in FIG. 5 in alignment with the recesses 196 provided for that purpose at the corner of the face plate 186 and flange 188 of the vertical arm.

While the bracket 122 which joins the bottom and side members 116 and 112 of the sash frame, has a horizontal arm which is generally U-shaped in cross section and a vertical arm which is L-shaped in cross section, both arms 200 and 202 of the bracket 120 are L-shaped in cross section. The vertical arm 202 is substantially identical in cross-sectional shape to the vertical arm 184 of the corner bracket 122 as each fits into the same L-shaped channel 128 in side member 112. Thus, the outer edge 204 of the vertical arm 202 is bevelled from the inner side thereof and the corner joining the face 206 and flange 208 is provided with a pair of staking recesses 210 to receive the dimples 212 formed in the inner side 124 of the side member. These are suggested in FIG. 5.

The horizontal arm 200 of the bracket 120 has a face 20 plate 214 and a flange 216 which are shown in FIG. 8 to fit within the channel 148 of the top member. The outer edge of the face plate 214 is bevelled from the inner side as shown at 218, and the bevel mates with the undercut 156 in the lip 154 of the inner side 142 of the top member 114. The flange 216 lies against the upper side of the web 146. The horizontal arm 200 is locked in place by staking the side 142 as suggested at 220 in FIG. 5 in alignment with the staking recesses 222 provided on the corner of the horizontal arm 214 at the 30 corner of the face plate 214 and flange 216. By staking the top member as suggested, the horizontal arm wedges firmly into the bevel provided by the lip 154 and the bracket is thereby securely locked to the upper horizontal member 114 of the sash frame.

The bracket 120 carries a swivel post 224 disposed upwardly and outwardly of the horizontal arm 214. The swivel 224 serves as a pivotal support for the sash in cooperation with the swivel on the opposite side of the sash. That is, the swivels 224 at the upper corners of each sash fit within tracks provided in the window frame and the sash pivots on the swivels when the latches are withdrawn so that the heads 182 are free of those same tracks. When the sash is pivoted inwardly on the swivels 224 it may be tilted about a substantially horizontal axis normal to the window frame to free each of the swivels from the frame.

In each of the embodiments of the present invention the brackets are provided with one or more arms which is generally L-shaped in cross section and has an outwardly directed bevelled edge which mates with a similarly shaped channel in the sash frame. Thus, the brackets 48, 50 and 122 each have vertical arms which are generally L-shaped and those arms have outwardly directed bevelled edges which bind against tapered seats in 55 the side member of the sash frame, and those arms are locked in place by staking which forces the bevelled edge firmly against the seat. The bracket 120 of the second embodiment of this invention has both horizontal and vertical arms with the L-shaped cross-sectional configuration. Both the vertical and horizontal arms have outwardly directed bevelled edges formed along the sides of their face plates throughout substantially the full length thereof, and staking recesses are provided along the inner edges of the face plates at the corners. The bevelled 60 edges of both the vertical and horizontal arms fit within tapered seats provided in the corresponding parts of the sash frame, and when the arms are staked in place a very firm locking fit is provided between each of the arms of the bracket and the parts of the frame which receive them. Thus, in each embodiment the bevelled edges of the bracket arms prevent any relative twisting between 65 the bracket and the frame, rocking of the frame is greatly limited, and the firm grip is achieved with a minimum of staking.

5
Those skilled in the art will appreciate that numerous modifications may be made of this invention without departing from its spirit. Therefore, I do not intend to limit the breadth of this invention to the two embodiments illustrated and described. Rather, it is intended that the breadth of this invention be determined by the appended claims and their equivalents.

What is claimed is:

1. A corner bracket for aluminum window sashes comprising
a horizontal arm U-shaped in cross section with the base of the U-shaped arm providing a front face for the bracket,
an upwardly extending arm secured to one end of the horizontal arm and having an L-shaped cross section and with one of the flanges of the L-shaped section being parallel to the front face of the horizontal arm, the other of the flanges of the L-shaped arm being disposed on the inner side of the upwardly extending arm,
and a bevelled edge provided along the length of the upwardly extending arm on the side of said one of the flanges opposite the other of the flanges.
2. A corner bracket for aluminum window sashes comprising
horizontal and vertical arms joined together at their ends, said vertical arm having a face plate substantially in a plane containing the horizontal arm,
said plate having a bevelled outside vertical edge extending substantially the full length of the plate and facing away from the horizontal arm,
and recesses provided along the inside vertical edge of the face plate of the vertical arm opposite the bevelled edge for receiving staking dimples forcing the face plate in the direction of its bevelled vertical outside edge.
3. A corner bracket as defined in claim 2 further characterized by
said bevelled vertical outside edge forming an acute angle with the face plate.
4. In combination with a corner bracket as defined in claim 1,
a sliding bolt disposed horizontally within the U-shaped cross section of the horizontal arm and mounted to move in and out of the outer end of the U-shaped arm.
5. A corner bracket for aluminum window sashes comprising
horizontal and vertical arms joined together at their ends, one of said arms having a face plate lying in a plane containing the other of the arms,
said face plate having an outer bevelled edge running substantially the full length thereof and facing away from the other of the arms,
and recesses provided along the inside edge of said plate opposite the bevelled edge for receiving staking dimples forcing the plate in the direction of the bevelled side edge.
6. A corner bracket comprising
a pair of arms connected together at their ends and disposed at right angles to one another,
front faces provided for the arms and disposed parallel to one another,
an inner flange provided as a part of each of the arms and defining a continuous wall about substantially the entire inner edge of the bracket,
and a bevelled edge provided along the outer side of at least one of the arms and extending substantially the full length of that arm.
7. A corner bracket as defined in claim 6 and further characterized by
all of the bevel being provided from one side of the arm.
8. A corner bracket as defined in claim 7 and further characterized by

the other arm at its outer side edge being similarly bevelled.

9. A corner bracket as defined in claim 7 and further characterized by
the outer side edge of the other arm having a flange 5
parallel to the flange at its inner edge and defining
with the front face and inner flange of that arm a
U-shaped cross section.

10. A corner bracket as defined in claim 7 and further characterized by

all of said bevel being formed on the rear of the front face.
